UNITED STATES PATENT OFFICE.

HENRY FRANCOIS FLINT, OF OMAHA, NEBRASKA.

ENVELOP.

1,134,075.

Specification of Letters Patent. Patented Mar. 30, 1915.

Application filed November 30, 1914. Serial No. 874,869.

To all whom it may concern:

Be it known that I, HENRY FRANCOIS FLINT, a citizen of the United States, residing at Omaha, in the county of Douglas and State of Nebraska, have invented certain new and useful Improvements in Envelops, of which the following is a specification.

This invention relates to an improvement in envelops of the class having interlocking flaps, each envelop being so constructed that after being sealed, one of the flaps may be withdrawn, these envelops being used generally for the purpose of effecting a saving in the cost of postage.

One of the objects of the invention is to provide an envelop so constructed that one of its flaps will automatically become caught in "interlocked" relation with other parts or elements of the envelop in such a manner that it will provide a more than ordinary resistance to the stresses directed thereto by the contents of the envelop.

Another object is to provide such a construction that, while the movable or interlocked flap may be manually withdrawn from the stop or holder, it cannot be replaced in a manner to escape detection.

Other and minor objects relate to features of construction permitting all of the flaps to be opened before sealing, a greater uniformity in the shape of the flaps to present a more attractive appearance, economy in manufacture, and a novel arrangement or disposition of the adhesive areas on one of the flaps which abut upon the pair of hooks employed.

With the foregoing objects in view the invention presents a novel construction, combination and arrangement of parts as described herein and claimed, and as illustrated in the drawing, wherein the single figure is a side view of an envelop embodying my invention, the pair of side flaps being folded.

Referring now to the drawing for a more particular description, A indicates the front of the envelop, the respective right and left side flaps being indicated at B and C; and D and E respectively indicate the bottom and top flaps, the folding of the paper sheet being on the lines a to form the rectangular front A.

As plainly shown in the drawing, the flap B, near its terminal, is provided with an element d, this being an adhesive substance preferably of circular area, and also said flap is provided with an adhesive element b consisting of a line or rectilinear area adja-

cent to its lower edge. The flap D is also provided near its edge with an adhesive element b of substantially rectilinear form.

The flap C is provided at its terminal 50 with a pair of opposed fingers or hooks c c, these being of curved form and inwardly convergent so that when the flap C is folded with its end covering the end of flap B, the adhesive part d of the last named flap will 55 be encircled or nearly so, by the hooks or fingers c c, the distance f between the ends of said hooks preferably being only one-fourth of the diameter of the area d of the flap B; and the parts are so arranged that when 70 these two flaps are folded as described, the fingers or hooks c c will be disposed adjacent to a terminal of the line or rectilinear adhesive area b of said flap B, intermediate 75 the two adhesive areas of said flap. In this connection it may be stated that the circular area d of flap B operates as a stop member in combination with the corresponding stop member d of flap D. When the flap D is folded upon flaps B C, its circular adhesive area d will register with the adhesive area b of flap B; and it will be seen that, while the fingers or hooks c c will not be disposed in contact with any adhesive substance, they will be caught by the adhering 80 parts d of the flaps B and D, when the flap D has been disposed in folded relation, as described.

According to the present construction, the contents of the letter may be disposed upon the part A before the flaps B C D are folded if desired, or thereafter, but in either instance, after the flap D has been folded, as last explained, the top flap is then to be folded, and its adhesive area g will adhere or engage with the outer sides of flaps B and D.

Among some of the advantages to be derived by use of the invention, it may be stated that the fingers c c will be caught or interlocked with the flaps B D without any attention of the operator, since the adhesive members d of said flaps B and D will be connected to form the stop mentioned. Also the fact that the terminal of the rectilinear area b of flap B is disposed near or adjacent to the element d of said flap, operates materially to reinforce the holding means for the fingers or hooks c c and normally to maintain them in a compressed condition when the flap D has been folded with its adhesive areas connected with the adhesive areas of the flap B. It will be noted that,

while the flap C is not engaged by any adhesive element of the other flaps, the elements *c c* will resist to great advantage any outward pressure directed to it from the 5 contents of the envelop, since the stresses will be directed edgewise of the two fingers or hooks, and the envelop when sealed will have a symmetrical appearance similar to letters requiring a higher rate of postage.

10 Also by reason of the construction, the flap C may be withdrawn as required for official examination of the contents, but it will be noted that if withdrawn it cannot be replaced, since the curved fingers will not pass 15 the stop *d*, as would be required when moved inwardly for replacement, and therefore the device is operative to advantage as tending to prevent tampering by inquisitive or unofficial persons.

20 It is believed that, on account of the features last mentioned, the advantages of the device will be appreciated by users of envelops of this class, as compared with envelops where a single, curved finger is employed for the removable flap, since the use 25 of a single finger does not prevent the contents of the envelop from being examined by inquisitive persons without detection, that form of flap after being withdrawn for 30 that purpose permitting it to be moved inwardly to its original position.

It will be noted that the areas *b* of flaps B and D are each provided at its inner end with an expanded part or comparatively 35 broad head X with a concaved terminal corresponding to the curvature of the fingers *c c* which lie between the elements *x* and the circular adhesive elements *d*, and when the envelop has been sealed ready for delivery the adhesive parts mentioned tend to 40 prevent a movement of the fingers *c c* in any direction.

It is considered that one of the advantages in the present construction, is the fact 45 that the connection of the circular, adhesive parts *d* of flaps B and D is located, when the envelop has been sealed, substantially midway between the longitudinal edges of said

envelop, and therefore the fingers *c c*, when caught between the heads *x* and the elements *d* of the flaps B and D, will resist the 50 stresses directed thereto more effectively than if located near one of said longitudinal edges.

I claim:

1. An envelop comprising a sheet bent to provide a rectangular front, a bottom flap and a pair of side flaps, adhesive areas disposed on the outer surface adjacent to the end of one of the side flaps, the other side flap being provided with a pair of curved hooks adapted to be disposed between the adhesive areas and to substantially encircle one of said areas, said bottom flap being provided with adhesive areas and adapted 60 to be folded to overlap the side flaps for connecting its adhesive areas with the adhesive areas of said side flap.

2. An envelop comprising a sheet bent to provide a rectangular front, a sealing flap, 70 a bottom flap, a first side flap and a second side flap, the first side flap being provided near its terminal with a circular adhesive area and adjacent thereto with a secondary adhesive area having a concaved terminal, 75 the second side flap being provided with a pair of curved hooks adapted to be disposed between the circular adhesive area and the concaved terminal of the secondary adhesive area of the first side flap, said bottom 80 flap being provided with a circular adhesive area and adjacent thereto with a secondary adhesive area having a concaved terminal and adapted to be disposed to overlap the side flaps for connecting its circular and secondary adhesive areas respectively with the circular and secondary adhesive areas of the first side flap, the sealing flap being provided 85 with an adhesive area and adapted to be disposed to overlap the bottom flap and side 90 flaps for a connection of its adhesive area with said bottom flap and the first side flap.

HENRY FRANCOIS FLINT.
